United States Patent Office

Des. 192,810
Patented May 15, 1962

192,810

GAME BOARD

Paul B. Schoolcraft, 509 Vine St., Liverpool, N.Y.

Filed Oct. 10, 1961, Ser. No. 67,031

Term of patent 7 years

(Cl. D34—5)

FIG 1

FIGURE 1 is a plan view of a game board embodying my new design;

FIGURE 2 is a side elevational view thereof.

The essential features of my design reside in the portions shown in full lines.

I claim:

The ornamental design for a game board, as shown and described.
